Lauson & Tarver LLP(57) **CLAIM**

I claim the ornamental design for a vanity cabinet, as shown and described.

DESCRIPTION

FIG. 1 is a front perspective view of the vanity cabinet;
 FIG. 2 is a front view thereof;
 FIG. 3 is a right side elevation view thereof; the left side elevation view being a mirror image thereof; and,
 FIG. 4 is a top plan view thereof.
 The rear and bottom views form no part of the design and are omitted.
 Portions of the drawings shown in broken lines show environmental structure and form no part of the claimed design.
